JUICER AND PULP EJECTOR ATTACHMENT FOR POWER DRIVEN APPLIANCE

Alfred W. Madl, Mequon, Wis., assignor to John Oster
Manufacturing Co., Milwaukee, Wis., a corporation of
Wisconsin

Filed Apr. 26, 1962, Ser. No. 69,856

Term of patent 14 years

(Cl. D89—1)

Fig. 1.

FIG. 2.

FIG. 3.

FIG. 1 is a perspective view of a juicer and pulp ejector attachment for power driven appliance showing my new design;

FIG. 2 is a front elevational view thereof;

FIG. 3 is a rear elevational view thereof;

FIG. 4 is a side elevational view taken from the right of FIG. 3; and

FIG. 5 is a top plan view.

I claim:

The ornamental design for a juicer and pulp ejector attachment for power driven appliance, as shown.
